(57) **CLAIM**

The ornamental design for a frame mount for a vehicle as shown and described.

DESCRIPTION

FIG. 1 is a front perspective view of a frame mount for a vehicle according to the present invention.

FIG. 2 is a right side perspective view of the frame mount for a vehicle of FIG. 1.

FIG. 3 is a front isometric view of the frame mount for a vehicle of FIG. 1.

FIG. 4 is a rear isometric view of the frame mount for a vehicle of FIG. 1.

FIG. 5 is a left isometric side view of the frame mount for a vehicle of FIG. 1; and,

FIG. 6 is a top view of the frame mount for a vehicle of FIG. 1.

The dashed lines illustrate environment that does not form a part of the present invention, and no claim is made to the material illustrated with dashed lines.

The appearance of any portion of the article between the break lines forms no part of the claimed design.
